UNITED STATES PATENT OFFICE

WILLIAM H. WHITTEN, JR., OF PITTSBURGH, AND THADDEUS R. GOLDSBOROUGH, OF WILKINSBURG, PENNSYLVANIA, ASSIGNORS TO WESTINGHOUSE ELECTRIC AND MANUFACTURING COMPANY, A CORPORATION OF PENNSYLVANIA

TELEVISION SYSTEM

Application filed June 25, 1927. Serial No. 201,315.

This invention relates to systems for producing images of pictures or other objects at distances therefrom. It is applicable both to television systems and to systems for the transmission of pictures.

In the transmission of views, either of pictures or of actual objects, points in the view and in the reproduction thereof must be correlated and, at each point in the reproduction, an illumination must be produced corresponding to the intensity of light at the correlated point in the view. This requires the simultaneous control of three quantities, two for the two coordinates of the points and the third for the intensity of the light. As this problem has ordinarily been attacked, each of these quantities is continuous. The quantities corresponding to the coordinates of the points must always be either absolutely continuous or vary by very small steps. It has heretofore been considered that the quantity corresponding to the brightness of each point must be capable of an indefinitely large number of different values, and so must vary through a continuous range.

It is an object of this invention to provide a system for the transmission of views in which only a limited number of different degrees of illumination shall be produced in the reproduction.

It is a further object of this invention to produce a view-transmission system in which the indefinitely large number of different values of the intensity of light at different points in the view shall be represented, in the output of the sending station, by an equally large number of values of the quantity representing the brightness but in which the receiving station shall represent the light values by a relatively few number of values of the illumination in the reproduction of the view approximately corresponding to the brightness.

It is a further object of this invention to provide means for changing the frequency of an electrical oscillation in accordance with illumination of a light-sensitive device.

It is a further object of this invention to provide means whereby changes in the variation frequency of a super-regenerative device

may be impressed upon the system without, at the same time, impressing thereon the oscillation frequency of said super-regenerative device.

It is a further object of this invention to provide a carrier-current system in which the points of a view and the homologous points in the reproduction are successively associated through the communication channel, and the intensity of light at the point in the view thus associated at any moment shall control the frequency of the modulation of the carrier current at that moment, while the amplitude of said modulation remains constant.

It is a further object of this invention to provide a plurality of frequency-selective devices by which the indefinitely large number of changes in the frequency of the modulation may be represented by the selective action of said devices, one, or, at most, two thereof, responding at any one moment.

It is a further object of this invention to provide means controlled by said selection of a frequency-responsive device for controlling the brightness of a light source.

It is a further object of this invention to provide a frequency-responsive device of a sufficiently broad tuning to cause it to respond to a definite portion of the frequency range of said modulation.

In practicing our invention, we employ a super-regenerative vacuum-tube device. A device of this character produces oscillations of a relatively constant frequency but the oscillations are interrupted periodically at a frequency known as the variation frequency. The period of such interruptions is dependent upon, among other things, the value of the grid-leak resistance. By making a portion of the grid-leak sensitive to light, the variation frequency may be made to represent the light. We impress this variation frequency as a modulation upon a carrier-current system and the light is thus represented by the frequency of the modulation.

By receiving the modulated carrier wave upon an apparatus containing a number of frequency-responsive devices, each controlling the brightness of a light source, we ob-

tain a number of changes in intensity of the light which, although not forming a continuous gradation of light, can reproduce the picture satisfactorily.

5 For a more complete understanding of our invention, reference is made to the following description and the accompanying drawings, in which,

10 Figure 1 is a diagram of the circuits and apparatus at the sending station, and

Fig. 2 is a diagram of the circuits and apparatus at the receiving station.

The view to be reproduced is represented in Fig. 1 by the arrow 1. This may be either 15 a moving object, a stationary object or a picture of an object.

The optical system, including the lens 2 and prisms 3 and 4 and the screen 5, is constructed in accordance with the disclosure in 20 the copending application of

The usual means for control of the transmission frequency of the superheterodyne device comprise a grid condenser the variable capacity of which is controlled by a grid-leak resistor 19. If a triode device is used, the resistor 19 is in parallel with the shunt of the grid circuit. The variation of the current through the device 8, therefore, changes with the illumination of the device 8.

The vacuum tube 21 is connected to the tube 23, in the usual way, to constitute the modulator, and the tube 23 the oscillator in a familiar form of constant-current modulation system. This system is supplied from a source 22 of plate-current energy. An impedance is provided in the lead from the positive side of the source 22 to the common connection for the plates of the tubes 21 and 23. The impedance comprises an inductor 21 and a condenser 22.

and reactive connection 39 between them. The oscillations generated by the tube 23 and its associated circuits constitute the carrier-frequency current.

5 At the receiving station, an antenna 50 is coupled to a circuit 51 tuned to the carrier frequency. A vacuum tube 52, connected to the circuit 51 is equipped with a grid condenser 53 and a grid-leak resistor 54 which 10 cause the tube 52 to function as a detector. The plate circuit of the tube 52 is inductively coupled to three tuned circuits 55, 56 and 57, each tuned to a different frequency. Three tuned circuits have been shown by 15 way of illustration. The number of tuned circuits will be determined by the number of gradations of light required in the reproduced picture. Obviously, the larger the number of said differently tuned circuits, the 20 finer will be the gradations.

Each tuned circuit includes sufficient resistance to make it of broad tuning which may be a resistor 59 or the resistance of the inductor or the losses in the condenser. Points 25 of opposite potential in each of said tuned circuits are connected to opposed electrodes of a respective frequency-responsive relay 61 of the type described in the co-pending, joint application of A. M. Skellet and V. K. Zworykin, filed January 3, 1927, Serial No. 158,608, assigned to Westinghouse Electric and Manufacturing Company. Each of these relays includes a piezo-electric crystal 62 between said two electrodes. Each relay also includes 30 a third electrode connected to the grid of an associated vacuum tube.

The potential impressed from the resonant circuits upon the frequency-responsive relays is preferably supplemented by a source 40 of direct-current potential. This is indicated upon the drawing by a battery 63 and a resistance connected thereto. The battery and resistance are shunted about a condenser 64 by means of which the alternating potential 45 from the resonant circuit is transmitted.

The first of the said tuned circuits is associated with a vacuum tube 70, the plate-filament connection of which is in shunt to a portion 71 of a resistor 72. The vacuum tube 50 73 associated with the next tuned circuit has its plate-filament connection in shunt to a portion of the resistor 72, including the portion 71 and an additional portion 74. The vacuum tube 75, associated with the third of 55 said tuned circuits, has its plate-filament connection in shunt with the whole of said resistor 72.

The resistor 72 is in series with a light 60 source 76 which is, preferably, of the neon-glow-tube type, although any light source which is responsive to potential changes, giving a corresponding intensity for each impressed potential, is suitable. The resistor 65 72 and light source 76 in series are supplied

from a high-potential direct-current source 77.

Instead of the usual three-electrode high-vacuum tubes illustrated at 70, 73 and 75, it is also contemplated that grid-controlled 70 glow-discharge tubes, such as are disclosed in the application of D. D. Knowles, filed November 19, 1926, Serial No. 149,290, assigned to Westinghouse Electric and Manufacturing Company, may be used. When 75 such glow-discharge tubes are used, instead of the direct-current source 77, an alternating-current source should be supplied. Moreover, the frequency of said alternating-current source should be at least as high as, 80 and preferably higher than, would correspond to the shortest period during which the light is expected to continue at any one intensity.

The light from the source 76 impinges upon 85 a screen 81, preferably supplied with an orifice 82, which constitutes practically a point source of light. If desired, instead of the orifice 82 being completely transparent, it may be filled with translucent material of 90 such an optical density that the light which passes through it at the time when all of the resistor 72 is present in the circuit of the light source 76 will be insufficient to affect a photographic plate or be visible upon a screen in 95 the receiving device.

The receiving device comprises any desired system for optically associating the point-source 82 of light at any moment with that point in the reproduction which corresponds to the point in the image 6 of the object 1 in register with the orifice 7 at that moment. Preferably, the reproducing optical system is of the same type as the optical system at the sending station and, consequently, 105 two rotating prisms 83 and 84 and a lens 85 are shown on the drawing.

The screen 86, cooperating with the optical system, is intended to represent either the ground glass in a receiver of the camera type, 110 the wall or screen in a moving picture exhibition hall, a photographic plate or any other suitable or known reproduction surface.

In the operation of the device, the image of the view 1 is produced upon the screen 5 and 115 moved over the screen. The motion is such that the points of the image come, in turn, into registry with the hole 7. Preferably, this is accomplished by rotating the two prisms 3 and 4, one at a somewhat greater 120 speed than the other.

When the two prisms are in such relative position that their deflecting actions add, the edge of the image is near the hole. When the prisms are in such relative position that deflecting actions cancel, the central part of the image is in registry with the hole. The trace of the hole upon the image is thus a spiral extending from the outside to the center and then from the center to the outside. The sev- 130

eral repetitions of the spiral are not in exact registry with one another. Consequently, every point of the image is brought into registry with the orifice at one or another 5 moment.

The optical system in Fig. 2 is maintained in synchronism with the optical system in Fig. 1 by any suitable or well-known means; for example, the energy delivered from the 10 sending station may have a peculiar modulation imparted to it each time that the moving optical system passes through a certain position and such modulation may be caused to control the optical system at the receiving 15 station, bringing it into said characteristic position each time that the peculiar modulation arrives.

The maintenance of synchronism between the two optical systems results in directing 20 the light from the orifice 82 upon that point on the screen 86 which corresponds to the position of the orifice 7 in the image 6 at that moment. As the image moves over the screen 5, therefore, the spot of light moves over the 25 screen 86, thus reproducing, upon the screen 86, the path which the orifice 7 traces in the image 6.

In order to produce a picture of the view 1, the spot of light moving on the screen 86 must 30 so vary in intensity that at each moment the brightness of the spot on the screen 86 corresponds to the illumination of the photocell 8. It is not necessary, however, that this correspondence be a proportionality and, in 35 the system here disclosed, instead of a proportionality, the spot upon the screen 86 will have one of a relatively small number of intensities, that one which corresponds most nearly to the brightness of the illumination 40 of the photocell 8.

The tube 10 will produce oscillations of a frequency determined by the tuning of the circuit 16-17, but not continuously. Instead of being continuous, these oscillations are interrupted at the variation frequency. As the 45 illumination of the photocell 8 changes, the combined resistance of the photocell and the resistor 19 in parallel changes, with the result that the super-regenerative device changes its 50 variation frequency.

In order to ensure that the oscillations shall reestablish themselves promptly after each interruption, the coupling between the feedback coil 14 and the grid-coil 16 must be close 55 enough to give to the device a strong tendency to oscillate.

The oscillations produced in the tube 10 pass readily through the condenser 15. They are prevented from passing through the battery 11 by the radio-frequency choke coil 12. Currents or potential changes of the variation 60 frequency are prevented from passing through the battery 11 by the iron-cored choke coil 13. Although this choke coil is 65 shown as provided with an iron core, it is

feasible to provide a choke coil of sufficient inductance for this purpose without such core, particularly when the system is used for rapid reproduction of views such as is needed in television.

The frequency of the interruptions is preferably above audition, even when used for the reproduction of stationary objects, as in the transfer of pictures. For television purposes, the variation frequency must be 70 high enough to enable the picture to be reproduced some twelve or more times per second. A satisfactory degree of detail can be 75 obtained in television reproduction by a variation frequency of several hundred thousand cycles per second. The oscillations generated by the tube 10 must be higher than this in order that the variation period may contain a sufficient number of oscillation 80 cycles for the action to be positive and dependable. 85

The average value of the plate current is increased when the tube is delivering oscillations and diminished when it is not. Consequently, the potential across the condenser 90 15 has a periodic change at the variation frequency in addition to the oscillations generated at the higher frequency.

The coupling between the tube 10 and the tube 21 may be a transformer of moderately 95 broad tuning. It should transmit readily the (changeable) variation frequency, but should not transmit the oscillations generated by the tube 10 and, of course, would not transmit direct current. If, instead of such transformer, the coupling illustrated in Fig. 1 is used, the tuned circuit 31-32 prevents the transmission of the oscillation frequency but will permit the transmission of the variation 100 frequency. 105

The condenser 33 is of sufficient capacity to readily transmit the variation frequency. The condenser 15, by affording a path of low impedance for the oscillation frequency, increases the effectiveness of the tuned circuit 31-32 in preventing the oscillation frequency 110 from reaching the tube 21. The condenser 15 is of such small capacity as to present a large reactance to the variation frequency, whereby a large potential difference of this frequency is available to be transferred by the coupling. 115

The tube 21 acts as an amplifier for the variation frequency and also as a modulator for the tube 23. The circuit 24-25 should present a large impedance to the variation frequency, in order that the most effective modulation may be obtained. The maximum impedance would be obtained by a circuit 120 which was sharply tuned to the variation frequency, but, as the variation frequency changes throughout a substantial range and the impedance of the circuit 24-25 must be 125 large over all of this range, the tuning of this 130

circuit is broadened by the introduction of the resistance 26.

Oscillations generated by the tube 23 are prevented from reaching the battery 22 by the radio-frequency choke coil 27. Preferably, these oscillations are of a frequency corresponding to some 25 or 30 meters wave length, because radiation of this wave length obtains very certain control over great distances.

The wave length chosen, whether it is as short as stated or not, should be short enough for a sufficient number of cycles of the carrier frequency to be included within one cycle of the variation frequency. It is preferable, but not necessary, that the carrier frequency differ substantially from the frequency of the oscillations generated in the tube 10.

The oscillations generated in the tube 23 are modulated by the action of the tube 21, as is well understood by those skilled in the art. The output circuit of the tube 23 includes the usual tuned circuit 37 for storing the energy and the usual reactive connection to the antenna by means of which the stored energy may be radiated.

The radiated energy is received upon the antenna 50 which is coupled to the circuit 51, tuned to the carrier frequency. The received energy, after being amplified, if necessary, is impressed upon the detector tube 52 and the output current thereof includes the modulations.

Although the drawing and the specific description disclose only the apparatus which is responsive to the modulations controlled by the brilliancy of the several points in the view, other modulations, for purposes incidental to the transmission of views, may be present. For example, the modulation controlling the synchronizing may be present in the output of the detector tube 52, and the output circuit may properly include a device responsive to such modulation.

The modulation controlled by the illumination is of the variation frequency, which changes throughout a certain range. The tuned circuits, 55, 56 and 57, are responsive to various portions, respectively, of said frequency range. For the purpose of clearness, it will be assumed that the tuning of the circuit 55 is in the lowest portion of this frequency range. The tuned circuits may, however, be arranged in any desired order.

When a bright portion of the image 6 is in registry with the orifice 7, the photocell 8 is brightly illuminated. It, therefore, becomes conductive. The combined resistance of the photocell and the resistor 19 is low, and the variation frequency will, therefore, be high. The corresponding frequency in the output of the detector tube 52 will be high and will, therefore, come within the range to which the circuit 57 is responsive. The inclusion of the

resistor 59 in this circuit, by broadening the tuning, will cause it to be responsive not only to one maximum illumination of the photocell 8 but to all illuminations from the most intense down to a certain limit. Thus, all portions of the view at which the light-intensity is strong are correlated to the circuit 57.

The battery 63 impresses across the crystal 62 a potential which is less than the ionizing potential of the gas in the tube 61. When the circuit 57 is responding to a frequency within its range, an additional potential is impressed across the crystal 62 which, with the potential from the battery 63, is sufficient to cause the tube 61 to become operative. The range throughout which the response will occur is thus enlarged by the effect of the battery. It is preferable that the range of frequency over which any one tube, 73, for example, is responsive shall slightly overlap the ranges for the neighboring tubes, 70 and 75, in the example chosen.

When this occurs in the tube 61 associated with the circuit 57, the tube 75 becomes operative, with the consequence that the whole of the resistor 72 is short-circuited and the full potential of the source 77 is impressed upon the lamp 76. The coupling 57 is effective at the highest portion of the frequency range. It, therefore, responds when the photocell 8 is most brightly illuminated. Consequently, the light source 76 is brightest when the brightest portion of the image is in registry with the orifice 7.

In the same way, when a portion of the image 6 of intermediate brightness is in registry with the orifice 7, the illumination of the photocell 8 is intermediate, its conductivity is therefore intermediate, the variation frequency of the super-regenerative device will be intermediate, and the tuned circuit which will respond is the intermediate circuit 56. The tube 73 will, therefore, become conductive, and a portion of the resistor 72 will be short-circuited, with the result that the light from the source 76 will be of an intermediate intensity.

When a dimly illuminated portion of the view 1 is optically associated with the orifice 7, the photocell 8 will be dimly illuminated, the variation frequency will, therefore, be slow and, the circuit 55 will respond. The tube 70 will then be conductive, and only the small portion 71 of the resistor 72 will be shunted. The light from the source 76 will, therefore, be dim, and the portion of the screen 86 corresponding to the portion of the image now in registry with the orifice 7 will be dimly lighted.

When a very dim or a perfectly dark portion of the image 6 is in registry with the orifice 7, the photocell 8 will be non-conductive; the variation frequency of the super-regenerative tube will be determined by the resistor 130

19; the modulation in the output will be slow, and the frequency in the plate circuit of the tube 52 will be too low for even the circuit 55 to be responsive thereto. Consequently, no 5 part of the resistor 72 will be short-circuited, and the lamp 76 will either shine so dimly that a barely perceptible result is present upon the screen 86, or, if the lamp 76, under 10 these circumstances, is too dim to penetrate the translucent medium in the orifice 82, the corresponding portion on the screen 86 may be completely dark.

The correspondence between the brilliancy in the image 6 and that in the image upon the 15 screen 86 may, if desired, be reversed by reversing the order of the connections between the several tubes 61 and the corresponding portions of the resistor 72. This is of use when the screen 86, instead of being adapted 20 for direct viewing, is a photographic plate and it is desired to produce a positive instead of a negative upon the developed plate.

Although I have described the gradations in light upon the screen 86 as consisting of a 25 high, intermediate, low and very low intensity, a greater number of degrees of variation may be supplied by providing a larger number of tuned circuits, more sharply tuned, and a corresponding number of tubes which 30 each shunt a portion of the resistor 72.

When the light impressed upon the orifice 7 is of an intensity which falls between two of the degrees of intensity provided for upon the screen 86, it may effect two of the tuned 35 circuits and cause two of the tubes 61 to become conductive. No disadvantage results from this because, if, for example, the tubes 73 and 75 are both conductive at the same time, the fact that the tube 73 shunts a portion of the resistor 72 produces no result because the 40 portion thus shunted is included in the portion shunted by the tube 75.

It will, therefore, be apparent that this invention provides a system in which there 45 is no apparatus requiring a large number of similar units and no necessity for a large number of separate communication channels. The communication channels are, therefore, available for other purposes, such, for example, as the simultaneous transmission of 50 sound with the picture.

It will also be apparent that the variation in brightness in the reproduced picture in this system is not affected by fading, because 55 the brightness is dependent not upon the intensity but upon the frequency of the modulation.

It will also be apparent that the apparatus does not require any very great exactness of 60 adjustment. If, from any accident, the average variation frequency of the tube 10 changes, the tuned circuits at the receiving station may be adjusted to correspond. If 65 this adjustment should be so inexact that the correspondence between each tuned circuit

and the light intensity for which it was intended is destroyed, the result is only that the general tone of the reproduced picture is changed by one step to a brighter or a dimmer tone. The relative difference of brilliancy among the several portions of the picture is not altered, except at the ends of the range.

Although we have illustrated only a single form of our invention, and have indicated 75 only a few possible modifications in the description, many other modifications will readily occur to those skilled in the art. We, therefore, do not intend any limitation, except what is indicated in the claims or required by the prior art.

We claim as our invention:

1. In a system for the transmission of visual images, means for transmitting a carrier wave continuously modulated in accordance with the varying illumination of said image, and means whereby said illumination is reproduced in discontinuous steps at the receiving end.

2. In a view-transmission system, a high-frequency oscillation generator, a super-regenerative vacuum-tube device, means controlled by illumination for altering the variation frequency of said device, means for impressing on said high-frequency oscillations a modulation having a frequency equal to said variation frequency and a device responsive to said modulation in accordance with the frequency thereof.

3. In a view-transmission system, a high-frequency oscillation generator, a super-regenerative vacuum-tube device, means controlled by illumination for altering the variation frequency of said device, means for impressing on said high-frequency oscillations a modulation having a frequency equal to said variation frequency and a plurality of frequency-selective responsive devices together covering the frequency range of said modulation.

4. In a view-transmission system, a high-frequency oscillation generator, a super-regenerative vacuum-tube device, means controlled by illumination for altering the variation frequency of said device, means for impressing on said high-frequency oscillations a modulation having a frequency equal to said variation frequency and a plurality of frequency-selective responsive devices together covering the frequency range of said modulation, and a light-source controlled by said devices.

5. In a view-transmission system, a sending device comprising means for producing high-frequency energy modulated by a modulation of varying frequency, illumination-controlled means for controlling the frequency of said modulation, a receiving device comprising a plurality of frequency-selective devices each responsive to a range

of frequencies overlapping the range of the next, the combined range of said devices covering the whole range of said modulation and a light-source, the intensity of which is controlled by said devices.

5 6. In a view-transmission system, a sending station comprising means for delivering high-frequency energy modulated at a frequency corresponding to illumination, and a receiving station comprising a light-source having a brilliancy corresponding to the potential impressed thereon, a plurality of differently tuned frequency-responsive devices, means controlled thereby for impressing respectively different potentials on said light-source and means for delivering to said tuned devices energy of a frequency determined by said modulation, whereby the brilliancy of said light-source will be determined by said 20 illumination.

In testimony whereof, we have hereunto subscribed our names this 22nd day of June, 1927.
